UNITED STATES PATENT OFFICE.

JAMES WILKINSON, OF PITTSFIELD, MASSACHUSETTS, ASSIGNOR TO GENERAL ELECTRIC COMPANY, A CORPORATION OF NEW YORK.

ELECTRICAL APPARATUS.

1,306,570.

Specification of Letters Patent. Patented June 10, 1919.

Application filed December 28, 1915. Serial No. 69,108.

To all whom it may concern:

Be it known that I, JAMES WILKINSON, a citizen of the United States, residing at Pittsfield, county of Berkshire, State of Massachusetts, have invented certain new and useful Improvements in Electrical Apparatus, of which the following is a specification.

My invention relates to those tanks in which electrical apparatus is submerged in cooling and insulating fluids. Oil submerged, water cooled transformers are examples of the sort of apparatus to which my invention in its complete form is especially applicable; oil switches are a type of apparatus in connection with which the principal part of my invention is of interest. My invention is thus of quite general application, but for the sake of simplicity and clearness of description, and since it is of particular interest in transformers, I shall mostly describe it as it is related to that type of apparatus; I shall also in many instances, likewise for simplicity and clearness, refer to the fluid submerging the electrical apparatus as oil and the fluid for artificially cooling the submerging fluid as water, the fluids now in most common use for these purposes. The general application of my invention to all submerged electrical apparatus using oil or some other submerging fluid, and the problems which may be solved by my invention though they will vary with the apparatus to which my invention may be applied, will be readily understood from the description of its application to transformers.

According to the most common practice prior to my invention, transformer tanks, and likewise oil switch tanks, are provided with covers carried by the tank walls, and the fluids submerging the electrical apparatus only partially fill the tanks; gas filled spaces, more or less open to the atmosphere, are left between the surfaces of the submerging fluids and the covers to allow for the expansions and contractions of the submerging fluids as their temperatures rise and fall during the operation of the apparatus. Such gas chambers possess various undesirable features. For example, not only does each chamber contain air but it receives such gases as may be generated in the submer-

ing oil, some of which may form explosive mixtures with the gas therein, which, should they become ignited may result in destructive explosions; further, in receiving air from the surrounding atmosphere as the transformer and submerging oil cools and contracts, the chamber receives such moisture and other foreign matter as may at the time be in suspension in the atmosphere, and passes them on to the submerging fluid to the detriment of its insulating and cooling qualities. Various expedients have been suggested for overcoming certain of such undesirable features, such as filters for the air passing between the atmosphere and the gas chamber, and such as the elimination of the gas chamber by completely filling the tank with the submerging oil, taking care of the expansion of the oil by means of tanks external to the transformer tanks proper. All such expedients, however, themselves possess more or less undesirable features such as requiring constant attention, or devices external to the tanks, or lack simplicity or sufficient ruggedness, or some other features desirable in apparatus of this class.

The principal object of my invention is to provide tanks or devices for submerged electrical apparatus unaccompanied by such undesirable features, which take care within themselves of the expansion and contraction of the submerging oil and in which the gas chamber is substantially eliminated.

I accomplish this object by providing a tank which is substantially completely filled with the submerging oil and which freely changes in capacity as the oil expands and contracts. More particularly, I prefer to carry the cover of the tank up and down substantially in contact with substantially the entire surface of the oil as the oil expands and contracts, as by carrying or floating the cover on the contained fluid. In addition I preferably provide means for suitably guiding the cover with respect to the tank and for suitably sealing all openings through or about the cover to exclude all contact between the atmosphere and the fluid within the tank as the cover rises and falls; the seal about the edges of the cover may be suitable to pass to the atmosphere any excess gases within the tank, such for

example as those generated therein, or a separate passage to the atmosphere may be provided for such excess gases, or the separate passage may be arranged to pass gases

- 5 at a lower pressure and in smaller volumes than the seal, taking care of normal conditions, but being supplemented by the seal to pass such larger volumes as may be generated under abnormal conditions. These
- 10 features of suitable seals and separate passages to pass excess gases to the atmosphere may be of interest in connection with other types of tanks. The leads may, or may not, pass through the movable cover; such bushings as may be necessary may be carried by the cover as heretofore even though the latter float on the submerging fluid. If desirable a connection may be made between the tank and the floating cover for grounding the cover to the tank.

My invention as thus outlined may be applied to substantially all types of tanks in which electrical apparatus is submerged in insulating or cooling fluids. Another object of my invention, applicable when such fluids are artificially cooled as by water cooling coils submerged in the fluid within the tank, is to control the operation of such cooling means so as to equalize the operating 25 temperatures of the submerging fluid and the electrical apparatus therein. I do this by using the expansion and contraction of the tank to control a valve or other device governing the flow of water (or other cooling fluid) through the cooling coils or cooling chamber. If the cover is adapted to rise and fall as before indicated, a connection between the cover and water governing device 30 may start the operation of the cooling device 35 when the submerging fluid has reached a predetermined temperature, and hence expanded to a predetermined degree and raised the cover to a predetermined point, and stop the flow of water at another position of the 40 cover. This temperature may be something like that which it is desired the submerging fluid shall assume when the apparatus is operating continuously at about full load. The transformer is therefore at no time cooled 45 much more than is necessary. No cooling water is wasted by unnecessary cooling and the insulating materials of the transformers 50 are not subjected to unnecessary expansions and contractions tending to break them 55 down.

In the accompanying drawings I have illustrated certain embodiments of my invention. Figure 1 is an elevation, partly in section, of a portion of an oil submerged, 60 water-cooled transformer, the cover of the tank floating on the submerging oil. Fig. 2 is a sectional view on a larger scale, of the fluid seal between the cover and the tank, and one of the guides for the cover. Fig. 3 65 is a sectional view through the primary

valve of Fig. 1. Fig. 4 is a sectional view of a part of another tank illustrating particularly another manner of carrying a lead through a floating cover.

Referring to Fig. 1: The upwardly opening tank 6, the water-cooling coils 7, and the transformer 8 are substantially like those heretofore common. In accordance with my invention however, the tank 6 is provided adjacent its top, with an upwardly 70 opening annular well which is formed by the lip 9 and the annular bottom 10 which are attached to and concentric with, and within the walls of the tank 6. The cover of the tank comprises a substantially flat base portion 11 and upwardly extending edges 12, forming what is in effect a boat. The diameter of this cover is somewhat shorter than the internal diameter of the annular lip 9, as shown in Figs. 1, 2, and 4; this difference in diameter is sufficient to allow the cover to readily move vertically and to allow the escape of any gas that may be generated within the tank. The edges 12 of the cover extend upward, primarily in order 80 that the cover together with the bushings and such other devices as it may carry, may float on the oil 17 submerging the transformer 8. As the load on the transformer 8 changes therefore, and the oil 17 submerges it expands and contracts, the cover will rise and fall, but will always maintain engagement with substantially the entire surface of the submerging oil. In the construction now being described these edges extend 85 above the top of the tank when the cover is in its lowermost position, that is, when the oil of the tank is contracted to substantially the smallest volume contemplated, and carry two downwardly extending concentric lips 100 18 and 19. The lip 18 extends into the annular well of the tank and is disposed somewhat closer to the internal lip or wall 9 than to the external wall of the tank 6; the lip 19 is external to the tank and completes a cover 105 for the annular well. A suitable liquid 20, as oil, within the annular well completes a liquid seal between the edges of the tank and the cover. The only gas chamber within 110 this tank comprises then the annular space 115 between the edges 12 of the cover and the lip 18 and above the surfaces of the liquid 17 and 20; as indicated above, this may be made of very small volume. It will be apparent that any gaseous pressure within the tank 120 will tend to lower the level of the oil 20 between the lips 9 and 18, and ultimately escape below the lip 18 to the atmosphere. Since the lip 18 is located nearer the lip 9 than to the wall of the tank, gases within 125 the tank may escape to the atmosphere at a pressure (per square inch) lower than the pressure at which the atmosphere may enter the tank. A gage 35, indicates the position of the surface of the oil 20 within the annu- 130

lar well and hence the gaseous pressure within the tank. The connections of this gage are particularly illustrated in Fig. 4. The liquid seal completed by the oil 20 is particularly well adapted for releasing large volumes of gas to the atmosphere, but since in many cases this seal must be of considerable depth, on account of the range of movement of the tank cover, it may be possible for the gaseous pressure within the tank to reach undesirably high values. To relieve this pressure and maintain it at low values, I provide a primary valve 40 which, while generally not able to pass such large volumes of gases as the seal of the liquid 20, may pass to the atmosphere at lower pressures than the seal, such small volumes of gas as are to be anticipated in the normal operation of the device. This primary valve 40 is, in effect, a second liquid seal but of considerably lower head than the oil 20 of the annular well. This valve 40 comprises a hollow cylinder containing oil 42 into which a pipe 43 extends. The pipe 43 opens into the annular space within the tank between the edges 12 and lip 18 of the cover. At the lower end of the pipe 43 is an upwardly opening elbow 44 carrying a cage 45 for positioning a ball 46 adapted to float on the oil 42. This cage is so disposed that if, by any reason, the level of the oil 42 falls below the open end of the elbow 44, the ball seats in this opening and excludes contact between the atmosphere and the interior of the tank through this valve. A connection 55 is provided between the atmosphere and the interior of the valve 40 above the surface of the oil 42. As before pointed out, the head of the primary valve 40 is lower than the head within the annular well at the top of the tank, that is, the distance between the top of the elbow 44 and the surface of the liquid 42 is less than the distance between the surface of the liquid 20 and the lower edge of the lip 18; thus gas between the edges 12 and the lip 18 may force an exit to the atmosphere through the primary valve 40 at lower pressures than through the seal of the annular well. However, should gas be generated within the tank at greater volumes than can be passed by the primary valve, such greater volumes may pass to the atmosphere at slightly higher pressures by way of the liquid seal of the annular well. The cylinder of the valve 40 is preferably provided with a window 41 as indicated, through which any passage of gas from the interior of the tank to the atmosphere through this valve may be observed; hence the valve 40 serves the double purpose of passing gas to the atmosphere and an indicator of the generation of gas within the tank. In order that such observations may be readily made, the valve 40 is preferably located on the walls of the tank 6 and so far below the top as may be

necessary to be readily inspected; to allow the cover to rise and fall the pipe 43 is flexible. The flexible cable 50 connected between the cover and the tank 6 firmly grounds the cover to the tank.

As the cover rises and falls it may be guided and held in position with respect to the tank by the external lip 19 alone or, if desired, other guiding means as the arms 22 carrying rollers 23 engaging with runways 24 on the walls of the tank may be provided. The number of such guiding arms will, of course, depend to a considerable extent on the size of the tank. 75

In the constructions illustrated the high voltage leads pass through the cover. In the construction illustrated in Fig. 1, each lead is provided with a bushing 29 which is carried by the cover and which may be fastened to the cover in any desired way, 85 though preferably the joint is air tight. Each lead 30 is substantially a rigid rod which is firmly fixed to the transformer at its lower end and to some stationary device 31 at its upper end. Firmly attached to the 90 upper end of each rod is a cylinder 32. Operating within this cylinder is a hollow piston 33 carried by the bushing 29. Each rod 30 passes freely through its bushing and the corresponding piston. As the cover rises and 95 falls, the piston 33 likewise rises and falls in the cylinder 32, but the two always form an air-tight joint between the atmosphere and the interior of the bushing 29, and hence exclude contact between the atmosphere and 100 the submerging oil 17 through the body of the bushing.

The flow of water through the cooling coil 7 is controlled by the valve 54. This valve is opened and closed by the rod 65 which carries near its top two heads or pins 56 and 57. An arm 58 attached to the outer lip 19 of the cover surrounds the rod between the two heads 56 and 57. These heads and the arm are so positioned that when the oil submerging the transformer has reached the temperature which it is desired it should assume when the transformer is something like fully loaded, and the oil has correspondingly expanded, the arm 58, raised by the cover and engaging the head 57 of the valve, holds this valve so far open that sufficient water flows through the coils 7 to maintain the oil at this temperature. On the other hand, when the load on the transformer has fallen substantially below such predetermined value, and the submerging oil has correspondingly contracted and the cover fallen, the arm 58 leaves the head 57, allowing the valve 54 to close, or, if necessary, engages with the head 56 and moves the valve toward this closed position. The heads 56 and 57 are separated such a distance that the cover may rise with the expansion of the submerging oil without opening the

valve until the desired predetermined temperature of the oil has been reached. It will be seen that this connection between the floating cover and the valve tends to equalize the temperatures of the submerging oil and hence the temperatures of the transformer, or rather tends to maintain the temperature of the transformer and the oil at a given degree. This connection allows no water to flow through the cooling coils when the transformer is without material load; hence the submerging oil is not thereby cooled to such a degree as to induce the condensation of moisture from the small gas chamber above its surface each time the load is low. The insulating qualities of the oil are, therefore, maintained and the maximum expansion and contraction of the materials of the transformer and the rate of such expansion and contraction are materially reduced, both of which are conducive to long life for the apparatus.

The transformer tank of Fig. 1 is particularly adapted for outdoor service, the cover being provided with a top, or roof, 60, for preventing the accumulation of rain or snow. Where the transformer is to be used for indoor service this top or roof may be omitted and the lead bushings carried on the base 11 of the cover as illustrated in Fig. 4.

In Fig. 4 a type of bushing and lead is illustrated which may be used whenever the lead is not too heavy to flex readily. In this case the lead 61 is firmly fastened within the bushing 62 and does not slide therein as in the construction of Fig. 1. This lead 61 is flexible between the lower end of the bushing and the transformer, and between the upper end of the bushing and the stationary member 63. These flexible portions of the lead allow the cover to rise and fall without disturbing the connections.

While I have described the principle of my invention and the best mode I have contemplated for applying this principle, other modifications will occur to those skilled in this art and I aim in the appended claims to cover all modifications which do not involve a departure from the spirit and scope of my invention.

What I claim as new and desire to secure by Letters Patent of the United States, is,—

1. The combination with a tank, a liquid therein and electrical apparatus submerged in said liquid, of a single protecting cover for said tank arranged to float on the surface of said liquid, and a fluid seal between the edges of the cover and the tank excluding contact between said submerging liquid and the atmosphere.

2. The combination with a tank, a liquid therein and electrical apparatus submerged in said liquid, of a single protecting cover for said tank arranged to float on the sur-

face of said liquid, and a fluid seal between the edges of the cover and the tank excluding contact between said submerging liquid and the atmosphere and a gage connected to said seal for indicating the position of the sealing fluid therein.

3. The combination with a tank, a liquid therein and electrical apparatus submerged in said liquid, of a single protecting cover for said tank floating on said submerging liquid, a liquid seal between the edges of said cover and tank and an insulating bushing for a lead from said apparatus carried by said cover.

4. The combination with a tank, a fluid therein and electrical apparatus submerged in said fluid, of a single protecting cover for said tank carried by said fluid near the surface thereof, a fluid seal between the edges of said cover and said tank, and means electrically connecting said cover and tank.

5. The combination with a tank, a liquid therein and electrical apparatus submerged in said liquid, of a single protecting cover for said tank floating on said liquid, a fluid seal excluding contact between said liquid and the atmosphere and a valve mounted on said cover connected with the interior of said tank above the surface of said submerging liquid allowing the escape of gas formed in said tank.

6. The combination with a tank, a fluid therein and electrical apparatus submerged in said fluid, of a single protecting cover for said tank floating on said fluid, a fluid seal excluding contact between the atmosphere and said submerging fluid and a fluid valve of lower head than said fluid seal allowing the escape of gas generated in said tank.

7. The combination with a tank, a fluid therein and electrical apparatus submerged in said fluid, of a single protecting cover for said tank floating on said fluid, a fluid seal excluding contact between the atmosphere and said submerging fluid, and a fluid valve of lower head than said fluid seal allowing the escape of gas generated in said tank and provided with means for preventing the entrance of the atmosphere into said tank therethrough.

8. The combination with a tank, a fluid therein and electrical apparatus submerged in said fluid, of a single protecting cover for said tank floating on said fluid, a fluid seal excluding contact between the atmosphere and said submerging fluid and a fluid valve fastened to the exterior of the tank below the top thereof and of lower head than said fluid seal allowing the escape of gas generated in said tank.

9. The combination with an upwardly opening tank provided with an upwardly opening annular well adjacent the top thereof, a liquid in said tank and electrical appa-

- ratus submerged in said liquid, of a single protecting cover for said tank floating on said submerging liquid and provided with a downwardly extending annular lip within said well, and a second liquid within said well completing a liquid seal for said tank as the cover rises and falls with the expansion and contraction of the submerging liquid.
10. The combination with an upwardly opening tank provided with an upwardly opening annular well adjacent the top thereof, a liquid in said tank and electrical apparatus submerged in said liquid, of a single protecting cover for said tank floating on said submerging liquid and provided with a downwardly extending annular lip within said well, said lip being located nearer to the inner than to the outer wall of said well, and a second liquid in said well completing a liquid seal for said tank.
11. The combination with an upwardly opening tank provided with an upwardly opening annular well adjacent the top thereof, a liquid in said tank and electrical apparatus submerged in said liquid, of a single protecting cover for said tank floating on said submerging liquid and provided with two downwardly extending concentric annular lips, one within and the other external to said annular well, the latter completing a cover for said annular well, and a second liquid within said well completing a liquid seal for said tank as the cover rises and falls with the expansion and contraction of the submerging liquid.
12. The combination with an upwardly opening tank provided with an upwardly opening annular well adjacent the top thereof, a liquid in said tank and electrical apparatus submerged in said liquid, of a single protecting cover for said tank floating on said submerging liquid and provided with a downwardly extending annular lip within said well, a second liquid within said well completing a liquid seal for said tank as the cover rises and falls with the expansion and contraction of the submerging liquid, and means between the tank and cover positioning the cover with respect to the tank.
13. The combination with an upwardly opening tank provided with an upwardly opening annular well adjacent the top thereof, a liquid in said tank and electrical apparatus submerged in said liquid, of a single protecting cover for said tank floating on said submerging liquid and provided with two downwardly extending concentric annular lips, one within and the other external to said annular well, the latter completing a cover for said annular well, a second liquid within said well completing a liquid seal for said tank as the cover rises and falls with the expansion and contraction of the submerging liquid, and downwardly extending guides carried by the cover engaging the tank walls positioning the cover with respect to the tank.
14. The combination with an upwardly opening tank provided with an upwardly opening annular well adjacent the top thereof, a liquid in said tank and electrical apparatus submerged in said liquid, of a cover for said tank floating on said submerging liquid and provided with a downwardly extending annular lip within said well, a second liquid within said well completing a liquid seal for said tank as the cover rises and falls with the expansion and contraction of the submerging liquid, a liquid valve of lower head than the liquid in said seal fastened to the exterior of said tank below the top thereof and a flexible pipe connecting said valve with the interior of said tank through said cover above the surface of the submerging liquid.
15. The combination with an upwardly opening tank provided with an upwardly opening annular well adjacent the top thereof, a liquid in said tank and electrical apparatus submerged in said liquid, of a cover for said tank floating on said submerging liquid and provided with a downwardly extending annular lip within said well, a second liquid within said well completing a liquid seal for said tank as the cover rises and falls with the expansion and contraction of the submerging liquid, a liquid valve of lower head than the liquid in said seal fastened to the exterior of said tank below the top thereof, a flexible pipe connecting said valve with the interior of said tank through said cover above the surface of the submerging liquid and means for preventing the entrance of the atmosphere into said tank through said liquid valve.
16. The combination with a tank, a liquid therein, electrical apparatus submerged in said liquid and a cooling coil for said liquid, of a cover for said tank floating on said liquid, a valve for controlling the flow of a cooling fluid through said cooling coils and a connection between said cover and valve for opening and closing said valve as the cover rises and falls with the expansion and contraction of the liquid and allowing a limited movement of the cover without a movement of the valve.
17. The combination with a liquid, electrical apparatus submerged in said liquid and a tank containing said liquid and electrical apparatus and expanding and contracting as the liquid therein expands and contracts, of a cooling device for said liquid, a cooling liquid adapted to circulate through said cooling device, means controlling the flow of said cooling liquid through said cooling device and a connection between said tank and controlling means increasing the

flow of said cooling liquid as said tank expands and decreasing its flow as the tank contracts

18. The combination with a tank having
5 electrical apparatus therein, of an insulating liquid in said tank surrounding said apparatus, a single protecting cover for said tank arranged to float on said liquid rising and falling with the expansion and contraction
10 of said liquid, a fluid seal between the edges of said cover and the wall of said tank, a

cooling device for said liquid submerged therein having a cooling fluid flowing therethrough, a regulating means for controlling the flow of cooling fluid through said device 15 and an operative connection between said cover and said means whereby the flow of said cooling fluid is regulated in response to the movement of said cover.

In witness whereof, I have hereunto set 20
my hand this 22nd day of December, 1915.

JAMES WILKINSON.
